UNITED STATES PATENT OFFICE.

BENJAMIN N. LEHMAN, FRANK COOK, AND JAMES ROBERTSON,
OF EUREKA, UTAH.

WRENCH.

No. 846,220.

Specification of Letters Patent.

Patented March 5, 1907.

Application filed March 22, 1906. Serial No. 307,392.

To all whom it may concern:

Be it known that we, BENJAMIN N. LEHMAN, FRANK COOK, and JAMES ROBERTSON, citizens of the United States, and residents of Eureka, county of Juab, State of Utah, have invented a new and useful Wrench, of which the following is a specification.

Our invention consists of a wrench having means for primarily and completely adjusting the position of the jaws of the device on a nut or other object to be engaged, as will be hereinafter set forth, and other novel features, as will be hereinafter described and claimed.

Figures 1 and 2 represent elevations of opposite sides of a wrench embodying our invention. Fig. 3 represents a longitudinal section of a portion on line $x-x$, Fig. 1. Fig. 4 represents a transverse section on line $y-y$, Fig. 1. Fig. 5 represents a partial side elevation and partial longitudinal section of a modification.

Similar letters of reference indicate corresponding parts in the figures.

Referring to the drawings, A designates the outer or fixed jaw of a wrench, B the shank which carries the same, and C the handle of the device, which handle is hollow or recessed and telescopically receives portion of said shank.

D designates the movable jaw, which freely encircles said shank and has a portion adapted to be engaged by the screw E, which latter is swiveled on the boss F of the handle and provided with a thumb-piece G, said screw having also a bearing stem or stud H, which is mounted on the shoulder J to receive portion of the strain on said screw when the wrench is in use, it being noticed that the boss F and shoulder J of the head C' are on the handle C.

On the side of the shank B is the ratchet K, which is adapted to be engaged by the dog L, which primarily occupies a recess M in the side of the head C', said dog being connected with the stem N, which passes through a transversely-extending recess P in the offset Q of said head and has connected with its outer end the spring-pressed button R, which, as apparent, occupies a position on the side of said offset opposite to said dog, so that when the handle is grasped the thumb may be conveniently applied to said button, the latter being also adjacent to the thumb-

piece G, which is also conveniently accessible when the handle is grasped.

When the wrench is to be used, the button R is pushed in, the shank B then being released of the dog L, and the jaw A may be moved to or from the jaw D to a required extent for primary adjustment, when the button is let go and the proper tooth of the ratchet is again engaged by the dog, thus controlling the shank, and consequently the jaw A. The jaws are then fitted on a nut or other object, when the thumb-piece G is rotated, whereby the jaw D is moved into full adjustment on and close contact with said object, thus firmly grasping the latter, when the wrench may be operated without liability to slip from its position. When the work is accomplished, the piece G is rotated in reverse direction, whereby the jaw D recedes from the object sufficient to conveniently release the jaws from the same, when the wrench may be removed. It will be seen that the head C' firmly supports the dog L while engaged with the ratchet K, and the offset Q of said head receives the stem N of said dog and contains the spring N', which bears against a shoulder in the recess P and the button R and forms a guide for the latter, as will be most apparent in Fig. 4.

In Fig. 5 we show the movable jaw D as pivotally mounted on the frame which carries the same, thus readily adapting the wrench for pipe or other purposes. The screw E, which passes through the nut D' of the jaw D, as plainly shown in Fig. 1, has on the end within the chamber D² of the connecting-piece D³ of said jaw and nut the head or shoulder E', whose diameter is slightly larger than that of said screw, whereby complete disengagement of said screw from said jaw may be prevented. The boss F is made removable from the head C', so that the screw and its thumb-piece may be located and displaced when the latter is required, said boss being secured to the head in any suitable manner, in the present case by screw shown in dotted lines, Fig. 1. The button R may be disconnected from the stem N, when the dog L and the spring N' may be removed and afterward conveniently reapplied and retained in position. The side of the shank is provided with a measuring-scale (see Fig. 1) for nice adjustment of the jaws D and A relatively to each other. It is evident that the

- members A, B, D, E, F, and C, as well as the members R L N', as above stated, are discon-
nectible from each other, a feature of impor-
tance should there be breakage of or injury
5 to either member, so as to replace the mem-
ber or members and permit of the ready as-
sembly of the members in again making up
the implement. The back of the connecting-
piece D³ of the jaw D and nut D' has a pas-
10 sage D⁴ therein, whereby access is had to the
chamber D² to provide for the application of
the head or shoulder E' to the adjacent end
of the screw E and removal of the same there-
from when so required.
- 15 Having thus described our invention, what
we claim as new, and desire to secure by Let-
ters Patent, is—
1. In a wrench, an outer jaw, a movable
jaw, a handle, a shank on said jaw, the same
20 being telescopically received in said handle
and having serrations in its side, a head on
said handle, the same having a recess therein,
an offset on said head, the same having a re-
cess at an angle to that of said head, a dog
25 disposed in the recess of said head, and adapt-
ed to engage either of said recesses, a stem
extending angularly from said dog and occu-
pying the recess of said offset, a button con-
nected with said stem and a spring pressing
30 outwardly against said button and occupying
the recess of said offset.
  2. In a wrench, a handle, a movable jaw,
an outer jaw, its shank telescopically received
35 in said handle, a head on said handle having
an offset, a dog disposed in a recess in said
head and having an angularly-disposed stem
passed transversely through said offset, and
a spring-pressed button movable in said offset
40 and detachably connected with said stem,
and the dog being removably held thereby in
the handle.
  3. In a wrench, a handle, a movable jaw,
an outer jaw, its shank telescopically received
45 in said handle, a head on said handle having
an offset, a dog disposed in a recess in said
head and having an angularly-disposed stem
passed transversely through said offset, and a
spring-pressed button movable in said offset
50 and being detachably connected with said
stem, and the dog removably held thereby in
the handle, and engaging the side of the
shank opposite that upon which the button
is disposed.
  4. In a wrench, a handle, an outer jaw, its
55 shank telescopically received in the handle, a

head and an offset on the handle; a movable
jaw loosely movable on said shank and cham-
bered, and a screw engaged with the movable
jaw in said chamber and with means on the
handle, with the end of the screw engaging a 60
shoulder on the head of the handle.

5. In a wrench, a handle, an outer jaw, its
shank telescopically received in the handle, a
head and an offset on the handle, a movable
jaw loosely movable on said shank and cham- 65
bered, a screw engaged with the movable jaw
in said chamber and with means on the han-
dle, with the end of the screw engaging a
shoulder on the head of the handle, and a boss
on the handle on which said screw is swiveled. 70

6. In a wrench, a handle, an outer jaw, its
shank telescopically received in the handle, a
head and an offset on the handle, a movable
jaw loosely movable on said shank and cham-
bered, a screw engaged with the movable jaw 75
in said chamber and with means on the han-
dle, with the end of the screw engaging a
shoulder on the head of the handle, and a boss
on the handle on which said screw is swiveled,
said boss being detachably secured to the han- 80
dle and its offset.

7. In a wrench, a handle, an outer jaw, its
shank telescopically received in the handle, a
head and an offset on the handle, a movable
jaw loosely movable on said shank and cham- 85
bered, a screw engaged with the movable jaw
in said chamber and with means on the han-
dle, with the end of the screw engaging a
shoulder on the head of the handle, a boss on
the handle on which said screw is swiveled, 90
said boss being detachably secured to the han-
dle and its offset, and a thumb-piece on said
screw between said shoulder and boss.

8. In a wrench, a jaw, a shank on which
the same is freely mounted, a nut, a piece 95
connecting said jaw and nut, the same hav-
ing a chamber therein, a screw held against
longitudinal movement and fitted in said nut
and adapted to enter said chamber; and a
head on said screw within said chamber of 100
greater diameter than the bore of said nut, a
wall of said piece having a passage therein in
communication with said chamber, said
screw being independent of said shank.
